UNITED STATES PATENT OFFICE.

HERBERT P. SCHMECK, OF PHILADELPHIA, PENNSYLVANIA, ASSIGNOR TO PHILADELPHIA TOBOGGAN COMPANY, OF PHILADELPHIA, PENNSYLVANIA, A CORPORATION OF PENNSYLVANIA.

COASTER-TRACK STRUCTURE.

Application filed December 20, 1926. Serial No. 155,973.

My invention relates to amusement railway systems, having particular relation to the track structure therefor.

One object of my invention is to provide 5 a track construction that shall be characterized by its simplicity of design, rigidity of construction, and accessibility for purposes of repair.

Another object of my invention is to provide 10 a structure of the character described, wherein the rider is afforded maximum safety for extremely abrupt horizontal and vertical curves.

Other objects and applications of my invention, as well as details of construction and operation will be apparent more fully hereinafter, when taken in connection with the 15 accompanying drawing, wherein

The single figure of the drawing is a transverse sectional view of a coaster and supporting track structure embodying my invention.

Referring to the drawing, a track structure 1 comprises a pair of elongated track beams 2 and 3 which are mounted on transversely extending tie beams 4. On outer vertical sides 5 and 6 of the track beams 2 and 3 are respectively positioned boardwalks 7 and 8. Each of these boardwalks 7 and 8 is mounted in position on a structure 9 extending upwardly from the tie beams 4 and secured in position by vertical through bolts 11 and 12. The structure 9 may include an inner plank 13, which is mounted on the outer side 5 of the track beam 2, and an outer plank 14. These planks may be positioned on edge. The track beam 2 may comprise a plurality of elongated planks 15 mounted in superimposed relation, a lower plank 16 lying flat on the tie beams 4. An angle member 17 may be mounted on an upper corner of the track beam 2 with one flange 18 thereof positioned on a top side 19 of an upper plank 21 and with the other flange 22 in engagement with an inner edge 23 of said upper plank 21. The top and side flanges 19 and 22 define elongated horizontal and vertical wearing surfaces 24 and 25 which co-operate respectively with a supporting portion 26 and a flanged portion 27 of a vehicle wheel 28. The wheel 28 may be mounted in bearings 29 secured to a supporting structure 31 positioned on an adjacent side 32 of a coaster 33.

An opposite side 34 of the coaster 33 is 55 provided with a wheel 35 having portions 36 and 37 respectively associated with flanges 38 and 39 of an angle member 41 mounted on an upper inner corner of the track beam 3. The wheel flanges 27 and 37, in co-operation 60 with the angle flanges 22 and 39, prevent undesirable lateral movement of the coaster 33, when traversing a curved track section.

The vertical displacement of the coaster 33 65 while traversing a dip in the track section may be limited to a safe value by safety rails 42 and 43 which are respectively mounted on the inner sides of the track beams 2 and 3. Each of the safety rails 42, 43 comprises a 70 pair of inner and outer elongated planks or strips 44 and 45 which are secured in side by side relation and mounted on the inner side of the track beam so as to overlie one or more of the meeting edges 46 defined by 75 successive planks in said track beam.

As shown in the drawing, an upper edge 47 of the inner plank 44 of the safety rails 42, 43 is positioned in abutting relation with the angle side flanges 22, 39. Under edges 80 48 and 49 of the planks 44 and 45 constitute an under rail surface 51. The under rail surfaces 51, 51 of the safety rails 42 and 43 are respectively positioned in abutting relation to shoes 52 and 53 extending from the 85 opposite sides 32 and 34 of the coaster 33. Thus, an undesirable vertical displacement of the coaster 33 is prevented and the safety of the sides assumed.

When the car 33 is traversing a curved 90 track section lateral displacement is limited to a safe value by the wheel flanges 27 and 37 and the side angle flanges 22 and 39. However, when the car reaches a track section involving a dip, the safety of the rider 95 is insured by the safety rails 42 and 43, inasmuch as the further movement of the coaster 33 is prevented upon the engagement of the shoes 52 and 53 with the under rail surfaces 51, 51 of the safety rails 42 and 43.

While I have shown only one embodiment 100 of my invention, for the purpose of describing the same and illustrating its principles of construction and operation, it is apparent that various changes and modifications may be made therein, without departing from the spirit of my invention. I desire, therefore, 105 that only such limitations shall be imposed

thereon as are indicated in the appended claims or as are demanded by the prior art.

I claim:

1. In combination, a coaster having abutting surfaces and also a supporting wheel, a track beam, a wearing element mounted on said beam and positioned in operative relation to one of said abutting surfaces, and a safety rail disposed in abutting relation to the other of said surfaces, whereby lateral and vertical displacement of said coaster may be limited to a desired extent.
2. Amusement apparatus comprising a track beam, a vehicle having a plurality of surfaces, a rail element mounted on said track beam in operative relation to one of said plurality of surfaces, and a safety rail positioned in abutting relation to said rail element and affording another of said plurality of surfaces an abutting surface.
3. In an amusement system, the combination with a coaster having an abutting surface, of a track structure therefor having a side rail element, and a safety rail positioned in abutting relation to said rail element, said safety rail being engaged by said abutting surface in accordance with predetermined operating conditions.
4. In combination, a coaster having abutting surfaces, and a track structure therefor comprising a rail member having top and side wearing surfaces, and a safety rail positioned in abutting relation to said rail member and defining an under wearing surface, said side and under wearing surfaces being positioned in operative relation to said coaster abutting surfaces, whereby undesirable lateral and vertical movements of said coaster may be prevented.
5. In a system of the character described, the combination with a vehicle having abutting portions, of a track beam therefor including a rail member having substantially horizontal and vertical wearing surfaces, and a safety rail positioned in abutting relation to said rail member and affording one of said vehicle abutting portions an under rail surface, one of said wearing surfaces being positioned in abutting relation to the other of said vehicle abutting portions, whereby undesirable displacement of said vehicle may be prevented.
6. In railway system, the combination with a vehicle having a flanged wheel, of a supporting track beam for said wheel, a wearing element positioned to be engaged by the flange of said wheel to limit the lateral displacement of said vehicle and a safety rail positioned in abutting relation to said wearing element and so operatively associated with said vehicle as to limit the vertical displacement thereof.
7. An amusement system comprising a coaster having a flanged wheel, a supporting track beam therefor, means affording

top and side rail surfaces for said wheel, the latter surface and the flange of said wheel being in operative relation so that lateral movement of said coaster may be limited, and a safety rail mounted on the side of said track beam in abutting relation to said means, said safety rail being positioned in operative relation to said coaster so as to limit the vertical displacement thereof.

8. The combination with a vehicle having a flanged wheel and an abutting portion, of a supporting track beam therefor, an angle mounted on said track beam to afford top and side rail surfaces for said flanged wheel, and a safety rail positioned in abutting relation to said angle affording said vehicle abutting portion an under rail surface.

9. An amusement railway system comprising a vehicle having a flanged wheel, a track beam, means positioned on the top and inner side of said track beam adapted to afford said flanged wheel top and side rail surfaces, and an elongated member mounted on the inner side of said track beam with one edge thereof in abutting relation to said means, the opposite edge of said member affording said vehicle an under rail surface adapted to prevent undesirable vertical displacement.

10. In combination, a vehicle having a flanged wheel, a supporting track structure therefor, an angle member mounted on an upper inner corner of said track structure affording said flanged wheel angularly disposed wearing surfaces and safety rail comprising an elongated strip mounted on the inner side of a track structure with one edge in engagement with said angle, the opposite edge constituting an under track surface for said vehicle.

11. A track beam comprising a plurality of superimposed planks an angle mounted on one corner of the top plank defining angularly disposed wearing surfaces, and a safety rail mounted in abutting relation to said angle.

12. A track beam comprising a plurality of superimposed members, an angle mounted on the inner corner of one of said members, and a safety rail comprising an elongated member secured in abutting relation to said angle and at least one of said superimposed members.

13. A rail beam comprising a plurality of elongated superimposed members, means comprising elongated rail portions mounted on one corner of the upper member, and a safety rail comprising a pair of elongated members secured in side by side relation and mounted on at least one of said superimposed members and in abutting relation to one of said rail portions.

14. A track construction comprising a

plurality of superimposed members, an angle secured to the upper inner corner of one of said members so as to define top and side rail surfaces, and a safety rail comprising a pair of elongated members secured in side by side relation on said superimposed members so as to extend over the meeting edge of an adjacent pair of superimposed members and into abutting relation to said angle.

15. A track construction comprising a rail beam including a plurality of superimposed planks, an angle mounted on the inner upper corner of one of said planks, and a pair of elongated strips secured in side by side relation on the inner side of said rail beam so as to overlie a plurality of said planks and extend into abutting relation to said angle. ¹⁵
